UNITED STATES PATENT OFFICE.

ELLSWORTH B. A. ZWOYER, OF PERTH AMBOY, NEW JERSEY.

DRIER.

1,290,009.

Specification of Letters Patent. Patented Dec. 31, 1918.

Application filed February 16, 1917. Serial No. 148,935.

To all whom it may concern:

Be it known that I, ELLSWORTH B. A. ZWOYER, a citizen of the United States, residing at Perth Amboy, county of Middlesex, and State of New Jersey, have invented a certain new and useful Improvement in Driers, of which the following is a specification.

The present invention relates to devices for handling briquets composed of a pulverized material, the particles of which are mixed with a liquid or semi-liquid binder and then molded to form under pressure. When the briquets leave the press they contain considerable moisture which must be evaporated in the presence of heat and, on account of the density of the briquets, the degree of heat must be high and the articles must be subjected to it for a considerable period of time so that all or nearly all of the moisture may be driven off and the briquets be brought to a state of hardness sufficient to enable them to withstand the rough usages incident to handling and to preserve their form while being burned or melted as the case may be. After the briquets have been sufficiently dried they should be cooled to facilitate handling and permit of storage in bulk.

The objects of my invention are:—

1. To provide a compact device wherein the briquets may be subjected to the heat for a considerable period of time.

2. To distribute the briquets in such a manner that each may be subjected to the effect of the drying medium for the same period of time to provide for uniformity of drying.

3. To provide against injury of the briquets during the drying operation.

4. To provide for cooling the briquets after drying.

5. To provide a device wherein all of the operating parts may expand and contract in the same direction and together.

These and further objects will more fully appear in the following specification and accompanying drawings considered together or separately.

I have illustrated one embodiment of my invention in the accompanying drawings in which corresponding parts in all of the several figures are indicated by similar reference characters, and in which—

Figure 1 is a side elevation of the device.

Fig. 2 is a horizontal sectional view of the

same, the section being taken on the line indicated by 2—2 on Fig. 3.

Fig. 3 is a detail sectional view taken on the line 3—3 of Fig. 2.

Fig. 4 is a diagrammatic development of a portion of the apparatus.

Fig. 5 is a detail sectional view illustrating the feeding conveyer, and

Fig. 6 is a detail sectional view taken on the line 6—6 of Fig. 2.

In carrying out my invention I provide a single unitary structure wherein the briquets are received from the briquetting press, are dried, then cooled and finally discharged into storage receptacles or into transportation devices.

The apparatus comprises an inclosed drying chamber 1 and an open cooling frame or rack 2 in axial alignment, the drying chamber being located above the cooling frame. The chamber and rack are supported on a central shaft 3 which is supported on anti-friction devices, such as balls 4 carried by a base 5. The shaft 3 is provided with a worm gear 6 which meshes with a worm 7 carried on a shaft 8 to which power may be applied to rotate the central shaft 3.

The drying chamber comprises a casing of approximately elliptical form consisting of a side wall 9, top 10 and bottom 11. One end of the chamber 1 is in communication with the chimney 12 of a furnace 13. A circulating air pipe 14 communicates with the chimney 12 between the furnace and the drier whereby air will be drawn into the chimney and heated by and mixed with the products of combustion from the furnace. The opposite end of the chamber 1 is in communication with a stack 15. The products of combustion and air heated thereby will enter the casing at one end, transverse the casing from end to end and escape through the stack 15.

The central shaft 3 is a hollow cylindrical casting composed of a bottom member 16, a plurality of intermediate members 17 and a top member 18. The member 16 is closed at its top, is provided with a perforation in the top and with a peripheral flange having a ball race in which is supported a range of balls 19. The member has a cylindrical neck 20 which is provided with a notched recess 21.

In Fig. 3 I have illustrated two intermediate members which are identical in form

and function. Each member is composed of a cylinder having a perforated bottom, a peripheral flange provided with a series of screw threaded radial perforations and a 5 notched neck 22 which engages the notched recess 21 in the member 16. The upper end of the member 17 has a notched recess 23 similar to the recess 21. The upper face of each peripheral flange of each member 17 is 10 provided with a ball race carrying a range of balls 24.

The top member 18 of the central shaft has a notched neck 25 which engages the corresponding recess in the uppermost member 15 17 of the shaft. The member 18 has a peripheral flange having a series of screw threaded radial perforations and a ball race carrying a range of balls 26. The member 18 is provided with a cylindrical axial 20 column in the upper end of which is a range of balls 27. A plate 28 rests upon the balls 27 and is rigidly secured to the top plate 10 of the drying chamber. A post 29 is seated in the top of the member 16 and extends upward 25 through perforations in the members 17 and 18 and the plate 28. The upper end of the post is secured to the building in which the apparatus is housed.

The shaft members 17, 18 and 19 when assembled one above the other are locked against relative rotation by the notches in the necks and recesses and form a shaft which is rotated by the worm 7 and worm 8. The balls 27 permit the shaft to rotate without 35 its rotary movement being communicated to the top 10 of the drying chamber.

Resting upon the balls 19 is a ring 30. Resting upon the balls 24, 24 are similar rings 31 and 31^a and a similar ring 32 rests 40 upon the balls 26. Each of the rings 31, 31 and 32 carries a range of balls 33, 34 and 35 supporting respectively a hub 36, 37 and 38. The hubs 36 and 37 each carries a range of balls 39 which support a ring 40 and 41 respectively and each is provided with a series of screw threaded, radial sockets.

Each of the rings 30, 31, 31^a, 32, 40 and 41 is provided with a series of radiating arms to which are secured angle beams 42 extending radially in pairs. One pair of beams 42 on each of the rings 30, 31 and 40 extends to a greater distance from the center than the others as shown at 43, for a purpose to be hereinafter described.

55 Supported on the tops of the beams 42 of the rings 31, 31^a, 32 and 41 are two continuous rails 44 and 45. These rails are shown as straight sections of T beams extending from one pair of beams 42 to the 60 next pair but it is obvious that the rails may be of other form.

The spider frames built up of the rings and beams 42 are equal in diameter to the inside of the lesser diameter of the drying 65 chamber except as noted. Certain of the

beams within the drying chamber are secured to angle beams 50 which in turn are connected to the side wall 9.

The beams of the ring 40 instead of being provided with rails carry the bottom 11 of the chamber which is also secured to the side wall 9. The beams of the ring 30 instead of rails 44 and 45 support the circular bottom 51 of the cooling rack.

The beams 42 carried by the rings 40 support the bottom 11 of the drying chamber which in turn is secured to the lower edge of the wall 9 of the casing. Certain of the beams 42 carried by the rings 31^a, 41 and 32 are secured to the wall 9 by means of the 80 angle beams 50. The casing is, therefore, supported on the rotary central shaft 3.

The extensions 43 to the beams 42 of the rings 30, 31 and 40 engage a spud 5^a carried by the base 5 and prevent rotation of the 85 rings mentioned and of the drying chamber.

Screwed into certain of the threaded sockets in the peripheral flanges of the members 17 and 18 and into the sockets in the hubs 36, 37 and 38 are spoke rods 46 which 90 extend radially from the center of the shaft 3. The ends of the rods support a ring 47 which is, in effect, the tire of a wheel of which the rods 46 are the spokes and the member 17 or 18 or the hub 36, 37 or 38 95 is the hub. The tires are secured in place on the rods by means of nuts. A second ring 48 is carried by the spokes and is retained in position by means of sleeves 49 which surround the rods on either side of 100 the ring.

Supplemental rods 52 screwed into sockets in the shaft members and hubs extend from the hubs to the ring 48 and additional short rods 53 are carried in the rings 47 and 48. The rods 52 and 53 are surrounded by sleeves which act as spacers for the rings.

Each rod 46 has hinged thereto two leaves 54 and 55. Each rod 52 carries a leaf similar to the leaf 54 and each rod 53 supports a leaf similar to 55. The leaves on alternate tiers of spokes and rods are disposed on opposite sides of their supporting rods so that as the tiers are rotated in opposite directions the leaves will be dragged around by the 110 rods. Each leaf is of segmental shape and, when in horizontal position, incloses the space between its supporting rod and the next adjoining rod. The free radial edge of each leaf is provided with a runner 56 120 which supports that edge of the leaf on the rail 44, 45 or bottom 11 or 51, as the case may be, and holds the leaf in its horizontal position so that each tier forms a circular 125 floor.

Each rail 44 and 45 has a depressed portion 57 for the purpose of allowing the free edge of each leaf to swing downward when it reaches the depressed portion, as shown in Fig. 4. The bottom members 11 and 51 130

have depressed portions 58 to permit the leaves riding over them to swing downward. The depressed portions 58 form chutes. The runners on the leaves coacting with the 5 members 11 and 51 are in the form of blades which scrape the bottoms and remove any dirt or dust which may fall upon them.

The tire ring 47 carried by each hub 36, 37 and 38 is provided with a circular, toothed 10 rack 59 and these racks are in mesh with pinions 60 on a shaft 61 which is geared to the drive shaft 8. The speed of the shaft 61 is such that the racks 59 are driven at the same speed as that of the central shaft 3 15 but in the opposite direction.

The chimney 12 enters the bottom of the drying chamber and its contents are discharged into a crescent shaped space which partially surrounds the rotating floors and 20 the direct heat from the chimney is presented from coming in contact with the floors and the briquets carried thereon by a baffling screen 62 of heat resisting material such as firebrick.

25 Opposite each rotating floor the drying chamber is connected to the stack 15 by means of a flue 63. Each flue is provided with a damper 64, the position of which is controlled by a thermostatic device 65 so 30 that the desired temperature of the drying chamber may be automatically maintained.

The engagement of the extensions 43 on the beams of the hubs 30 and 31 with the spud 5^a prevents rotation of the parts carried by those hubs and the engagement of the extensions of the beams of the hub 40 which carry the bottom of the drying chamber prevent rotation of the chamber. The beams of the hubs above the bottom of the 40 chamber being secured to the walls of the chamber are likewise prevented from rotating.

The briquets are fed to the uppermost tier of floor leaves by means of a scraper conveyor 66 working in trough 67 which enters the drying chamber near the top and to one side of the shaft 3. The floor of the trough is cut away so as to form an angular opening 68, the narrower part of which is over the 50 inner part of the floor, where the speed is slowest, and gradually widens toward the outer periphery of the floor where the speed is greatest. The briquets are dragged along the floor of the trough and are deposited on the uppermost rotating floor through the 55 wedge shaped opening in a single layer so that each individual briquet will be brought into contact with the drying gases.

As the uppermost floor rotates in the direction of the arrow A Fig. 2, the briquets will be carried around to the point B. When each leaf reaches this point its free edge will drop, by reason of the depression 57 in the track immediately below it and the 65 briquets carried thereby will be deposited

in a single layer on the floor next below which, by reason of the fact that it is carried by and rotates with the central shaft, is traveling in the direction of the arrow C Fig. 2.

When the briquets on the second floor have been carried through a complete rotation of the floor they are deposited on the next lower floor, which travels in the same direction as the first floor, in the same manner. This operation is continued until the briquets reach the lowermost floor of the drier. When each leaf of the lower floor reaches the depressed portion 58 of the bottom 11 of the drier it swings downward and 70 deposits its load of briquets on the uppermost rotating floor of the cooling rack when the operation above described is repeated. When the briquets reach the depressed portion 58 of the bottom 15 they are 75 discharged onto a conveyer 69 by means of which they are delivered to the desired point.

By reason of the fact that the entire apparatus including the casing for the drier 90 and the cooler are supported on the central shaft 16 the device will expand and contract as a unit and the relative positions of the floors and tracks will always remain the same. The connection between the bottom 95 of the drying chamber and the chimney 12 is non-rigid whereby the chamber may move relatively to the chimney. The flexibility of the flues 63 will permit of slight vertical movement of body of the apparatus 100 due to expansion and contraction.

The sectional central shaft 3 reduces the cost of manufacture and transportation, facilitates assembling and dismantling of the device, provides for increasing or reducing 105 the capacity of the apparatus and for ease of inspection and repair.

The post 29 is employed primarily to center the sections of the device during inspection or repair. As many sections as desired may be raised without disengaging the upper end of the post and be lowered in place without trouble.

While I have described my invention for use in drying and cooling briquets I desire 115 to have it understood that the apparatus may be employed for drying, roasting or baking generally.

In accordance with the provisions of the patent statutes I have described the principle of my invention, together with the apparatus which I now consider to represent the best embodiment thereof, but I desire to have it understood that the apparatus shown is merely illustrative, and that the 120 invention may be carried out in other ways.

Having now described my invention what I claim as new and desire to secure by Letters Patent of the United States, is:—

1. An apparatus of the character de- 130

scribed, having an inclosed chamber, means for supplying heat to the chamber, a rotating sectional floor within the chamber, and means for depositing briquets or the like in 5 a thin layer on the floor.

2. An apparatus of the character described, having an inclosed chamber, means for supplying heat to the chamber, a rotating sectional floor within the chamber, means 10 for depositing briquets or the like in a thin layer on the floor, and means for automatically regulating the heat in the chamber.

3. An apparatus of the character described, having an inclosed chamber, means 15 for supplying heat to the chamber, a sectional floor within the chamber, means for rotating the floor, a second floor, means for rotating the second floor, means for depositing briquets or the like on the first floor in 20 a thin, even layer, and means for transferring the same in a thin, even layer from the first to the second floor.

4. An apparatus of the character described, having an inclosed chamber, means 25 for supplying heat to the chamber, a floor within the chamber, means for rotating the floor, a second floor, means for rotating the second floor in the direction opposite to that of the first floor, means for distributing 30 briquets or the like to the first floor, and means for transferring the same from the first to the second floor.

5. An apparatus of the character described, having an inclosed chamber, means 35 for supplying heat to the chamber, a sectional floor within the chamber, means for rotating the floor, a second floor below the first floor, means for rotating the second floor, means for depositing briquets or the 40 like on the first floor in a thin, even layer and means for transferring the same in a thin, even layer from the first to the second floor.

6. An apparatus of the character described, having an inclosed chamber, means 45 for supplying heat to the chamber, a floor within the chamber, means for rotating the floor, a second floor below the first floor, means for rotating the second floor in the 50 direction opposite to that of the first floor, means for distributing briquets or the like to the first floor, and means for transferring the same from the first to the second floor.

7. An apparatus of the character described, having an inclosed chamber, means 55 for supplying heat to the chamber, a sectional floor within the chamber, means for rotating the floor, a second floor, means for rotating the second floor, means for depositing 60 briquets or the like in a thin layer on the first floor, means for transferring the same in a thin, even layer from the first to the second floor, and means for automatically regulating the heat in the chamber.

8. An apparatus of the character de-

scribed, having an inclosed chamber, means for supplying heat to the chamber, a rotating sectional floor within the chamber, means for distributing briquets or the like in a thin layer to the floor, a rotating floor 70 outside of the chamber, and means for transferring the briquets from the chamber in a thin layer to the last mentioned floor.

9. An apparatus of the character described, having an inclosed chamber, means 75 for supplying heat to the chamber, a floor within the chamber, means for rotating the floor, a second floor, means for rotating the second floor, means for distributing briquets or the like to the first floor, means for transferring the same from the first to the second floor, a plurality of floors outside of the chamber, said floors rotating in opposite directions, and means for transferring the briquets from the chamber to the adjoining 80 outside floor.

10. An apparatus of the character described, having an inclosed chamber, means for supplying heat to the chamber, a rotating floor within the chamber, means for distributing briquets or the like in a thin layer to the floor, and a common rotary support 90 for the chamber and floor.

11. An apparatus of the character described, having an inclosed chamber, means 95 for supplying heat to the chamber, a floor within the chamber, means for rotating the floor, a second floor, means for rotating the second floor, means for distributing briquets or the like to the first floor, means for transferring the same from the first to the second floor, and a common rotary support for the chamber and floors.

12. An apparatus of the character described, having an inclosed chamber, means 105 for supplying heat to the chamber, a rotating floor within the chamber, means for distributing briquets or the like in a thin layer to the floor, a rotating floor outside of the chamber, means for transferring the briquets 110 from the chamber to the last mentioned floor, and a common support for the chamber and the floors.

13. An apparatus of the character described, having an inclosed chamber, means 115 for supplying heat to the chamber, a floor within the chamber, means for rotating the floor, a second floor, means for rotating the second floor, means for distributing briquets or the like to the first floor, means for transferring the same from the first to the second floor, a plurality of floors outside of the chamber, said floors rotating in opposite directions, means for transferring the briquets from the chamber to the adjoining 120 outside floor, and a common support for the chamber and the floors.

14. An apparatus of the character described, having a rotatable shaft, a chamber supported on the shaft, connections between 125 130

the shaft and chamber to permit relative rotation of the shaft and chamber, a floor supported by the shaft and rotating therewith, and means for delivering briquets to the floor.

15. An apparatus of the character described, having a rotatable shaft, a chamber supported on the shaft, connections between the shaft and chamber to permit relative rotation of the shaft and chamber, a floor within the chamber, said floor being supported by the shaft and rotating therewith, and means for delivering briquets to the floor.

15. An apparatus of the character described, having a suitable shaft, a chamber supported on the shaft, connections between the shaft and chamber to permit relative rotation of the shaft and chamber, a floor supported by the shaft and rotating therewith, a second floor supported by the shaft, means for rotating the same in the direction opposite to that of the first floor, and means for delivering briquets to the first floor.

25. An apparatus of the character described, having a rotatable shaft, a stationary track supported by the shaft, a floor carried by and rotatable with the shaft, said floor engaging and being supported by the track.

30. An apparatus of the character described, having a rotatable shaft, a floor carried by the shaft, connections permitting relative rotation of the shaft and floor, a track carried on the shaft, connections permitting relative rotation of the shaft and track, said floor engaging and being supported on the track, means for preventing rotation of the track, a second floor carried by and rotatable with the shaft, means for rotating the first mentioned floor in the direction opposite to that of the shaft, means for delivering briquets to the first floor and means for transferring the briquets from the first to the last mentioned floor.

45. An apparatus of the character described, having a rotatable shaft, a floor carried by the shaft, connections permitting relative rotation of the shaft and floor, a track carried on the shaft, connections permitting relative rotation of the shaft and track, said floor engaging and being supported on the track, means for preventing rotation of the track, a second floor carried by and rotatable with the shaft, means for rotating the first mentioned floor in the direction opposite to that of the shaft, means for delivering briquets to the first floor, means for transferring the briquets from the first to the last mentioned floor, and means for heating the briquets on the floors.

55. An apparatus of the character described, having a plurality of superposed, rotatable floors with alternate floors rotating in opposite directions, means for feeding

briquets to the top floor, and means for transferring the briquets to the other floors in succession.

21. An apparatus of the character described, having an element comprising movable segmental members, means for supporting the members in alinement to form a floor or platform, and means permitting movement of the members to interrupt the continuity of the floor, the continuity of the members being uninterrupted.

22. An apparatus of the character described, having an element comprising movable segmental members, means for supporting the members in alinement to form a floor or platform, and means permitting independent movement of the members to interrupt the continuity of the floor, the continuity of the members being uninterrupted.

23. An apparatus of the character described, having a rotating element comprising movable segmental members, means for supporting the members in alinement to form a floor or platform, and means permitting movement of the members to interrupt the continuity of the floor, the continuity of the members being uninterrupted.

24. An apparatus of the character described, having a rotating element comprising movable segmental members, means for supporting the members in alinement to form a floor or platform, and means permitting independent movement of the members to interrupt the continuity of the floor, the continuity of the members being uninterrupted.

25. An apparatus of the character described, having a rotating element comprising radial shafts, segmental wings pivoted to the shafts, means for supporting the free edges of the wings in alinement to form a floor or platform, there being an interruption in the supporting means whereby the leaves may turn on the shafts and interrupt the continuity of the floor.

26. An apparatus of the character described, having a rotating element comprising radial shafts, segmental wings pivoted to the shafts, a track for supporting the free edges of the wings in alinement to form a floor or platform, there being a depression in the track whereby the leaves may turn on the shafts and interrupt the continuity of the floor.

27. An apparatus of the character described, having a rotatable shaft, said shaft being composed of interlocking, axially superposed sections, floors or platforms carried by the sections and rotatable with the shaft, floors or platforms supported by the sections, said floors being rotatable in the direction opposite to that of the shaft, and means carried by the sections for supporting the floors, said means being stationary.

28. An apparatus of the character de-

scribed, having a rotatable shaft, said shaft being composed of interlocking, axially superposed sections, floors or platforms carried by the sections and rotatable with the 5 shaft, floors or platforms supported by the sections, said floors being rotatable in the direction opposite to that of the shaft, means carried by the sections for supporting the floors, and means independent of the shaft 10 for preventing rotation of the supporting means.

29. An apparatus of the character described, having a rotatable, vertical shaft, a series of vertically superposed, horizontal 15 segmental floors or platforms carried by and rotatable with the shaft, a series of vertically superposed horizontal segmental floors or platforms alternately disposed relatively to the first mentioned floors and carried by 20 the shaft and rotatable in the direction opposite to that of the shaft, stationary tracks carried by the shaft, said tracks engaging the segments of the floors to retain them in horizontal alinement, there being a portion 25 of each track depressed whereby the segment above such depression will assume an inclined position and interrupt the continuity of the floor or platform.

30. An apparatus of the character described, having a rotary floor, a non-rotating casing surrounding the floor, and a single, 30 rotary support for the floor and casing.

31. An apparatus of the character described, having a plurality of rotary floors, 35 a non-rotating casing surrounding the floors, and a single support for the floors and casing.

32. An apparatus of the character described, having a plurality of rotary floors, 40 a non-rotating casing surrounding the floors, and a single support for the floors and casing.

33. An apparatus of the character described, having a plurality of rotary floors, 45 a non-rotating casing surrounding the floors, a single, rotary member for supporting the floors and casing, and means for preventing rotation of the casing.

34. An apparatus of the character described, having a rotary floor, a stationary 50 casing surrounding the floor, and a single rotary support for the floor and casing.

35. An apparatus of the character described, having a rotary floor, a stationary casing surrounding the floor, a single rotary 55 support for the floor and casing, and means for permitting relative movement of the casing and support.

36. An apparatus of the character described, having a plurality of rotary floors, 60 a casing surrounding the floors, and a single rotary support for the floors and casing.

37. An apparatus of the character described, having a plurality of rotary floors, a stationary casing surrounding the floors, 65 and a single rotary support for the floors and casing.

38. An apparatus of the character described, having a plurality of floors, a casing surrounding the floors, a single, rotary 70 member supporting the floors and casing, said floors rotating with the member, a plurality of floors, means for rotating the latter floors in the direction opposite to that of the member, and means for preventing rotation 75 of the casing.

39. An apparatus of the character described, having a plurality of floors each composed of pivoted elements, a casing surrounding the floors, a track for engaging the 80 elements of each floor, a single, rotary member supporting the floors, tracks and casing, said floors rotating with the member, a plurality of floors, each composed of pivoted elements, supported on the member, tracks 85 engaging the elements, means for rotating the latter floors in the direction opposite to that of the member, and means for preventing rotation of the casing and tracks.

This specification signed and witnessed 90 this fourteenth day of February, 1917.

ELLSWORTH B. A. ZWOYER.
